(57) **CLAIM**

The ornamental design for a concealable key/clip, as shown and described.

DESCRIPTION

FIG. 1 is a rear corner isometric view of a concealable key/clip showing my new design.

FIG. 2 is a front corner isometric view of the concealable key/clip of FIG. 1.

FIG. 3 is a left side elevation view of the concealable key/clip of FIG. 1.

FIG. 4 is a right side elevation view of the concealable key/clip of FIG. 1.

FIG. 5 is a top plan view of the concealable key/clip of FIG. 1.

FIG. 6 is a bottom plan view of the concealable key/clip of FIG. 1.

FIG. 7 is a front side elevation view of the concealable key/clip of FIG. 1; and,

FIG. 8 is a back side elevation view of the concealable key/clip of FIG. 1.

The broken lines are for illustrative purposes only and form no part of the claimed design.
